UNITED STATES PATENT OFFICE.

RUDOLPH M. MARTENS, OF BOSTON, MASSACHUSETTS.

LOCKING SWITCH.

Application filed February 11, 1922. Serial No. 535,769.

To all whom it may concern:

Be it known that I, RUDOLPH M. MARTENS, a citizen of the United States, and resident of Boston, in the county of Suffolk and State of Massachusetts, have invented certain new and useful Improvements in Locking Switches, of which the following is a specification.

This invention relates to electric switches, and particularly to switches adapted for high voltage circuits. Such switches are usually attached to a wall and sometimes to a ceiling and the opening and closing of the switch is then customarily effected by means of a pole having a hook to engage the movable member of the switch to pull that member open or to swing it back to close the circuit. To avoid liability of the switch accidentally opening, due to the effect of gravity or for other reasons, the movable members or blades of such switches have been provided with hooks pivoted thereto and adapted to engage fixed catch lugs to hold the blades in circuit closing positions. Some objections to the pivoted hooks have been raised on the ground that the pivots are not always capable of withstanding the strain after long continued use. If the pivot of one of such switches should give way, or slip from place, nothing is left to prevent the switch from accidentally opening.

The object of the present invention is to provide switches of the general type described with simple and positive locking devices which will reliably prevent accidental opening of the switch blades even after long continued use with resultant wear.

With this object in view my invention consists in the improvement which I shall now proceed to describe and claim.

Of the accompanying drawings,

Figure 1 is a side elevation of a well-known form of single throw switch having my improvements applied thereto.

Figure 2 represents an elevation looking from the right of Figure 1.

Figure 3 represents a section on line 3-3 of Figure 1 on a larger scale.

Similar reference characters indicate similar parts in all of the views.

Two insulating posts 12, 12, connected to a suitable base 13 are provided with cap members 14, 15 for the connection of the usual circuit wires, said members 14, 15, being provided respectively with switch jaws 16, 17. The movable member of the switch

is illustrated as a well-known type of switch blade 18 which is pivotally connected at 19 to the cap member 15. As so far described the switching device is of a well-known type.

The cap member 14 is formed or provided with an extension 20 which is recessed to provide a lug 21 which will be hereinafter referred to as the keeper lug.

Secured to the end of the blade 18, as by screws or rivets, and projecting beyond the blade in line therewith, is a housing 22 which is preferably, for convenience of manufacture, made in two parts as indicated in Figures 2 and 3, the parts being held in the relative positions indicated by the screws or rivets which pass through the end of the blade 18 and by such additional screws or rivets as may be desired. Said two parts of the housing are formed with openings to provide an eye 23 which is also in line with the blade (Fig. 1) for a purpose presently described.

A short bolt 24 is mounted to slide in the housing close to and parallel with the edge of the blade toward or from the recess behind the keeper lug 21, said bolt having an aperture or small recess into which projects the tip 25 of a lever 26 pivoted at 27 in the housing and having a curved end 28 which overlaps the eye 23 and is curved to a shorter radius than the radius of the inner circle of the said eye.

A spring 29 is confined between the lever 26 and a screw plug 30 mounted in the housing, said spring exerting a pressure to cause the tip of the lever to hold the bolt 24 in the locking position indicated in Figure 1 when and while the switch blade is in circuit-closing position. Figure 1 is partially broken out to better illustrate the parts just referred to. As shown in said figure one side of the bolt is bevelled to enable it to ride over the lug 21 when the switch is being closed.

When the switch is to be opened from the position shown in Figure 1, the user simply inserts something such as the customary hook implement in the eye 23 and pulls. The first result is to rock the lever 26 on its pivot so that its tip 25 withdraws the bolt 24 from behind the keeper lug 21, as indicated by dotted lines in Figure 1. Continued pull, owing to the implement then engaging the inner surface of the eye, results in opening the switch. Any pushing action to swing the switch blade in the re-

turn direction causes the bolt to automatically re-engage the keeper lug, the spring 29 yielding when the bevelled surface of the bolt contacts with the keeper lug.

5 As the eye 23 in the housing, and the curved end 28 of the lever, are substantially in line with the mid-length of the blade, neither a pulling nor a pushing action causes any twisting action on the blade.

10 The pivot 27 has nothing to do with holding the switch in locked position and therefore is subject to no strain. The bolt is mounted to slide in a direction practically or substantially parallel with and in the 15 plane of the switch blade and is retained in its locking position by the spring 29 acting through the lever. Consequently all the strain borne by anything to hold the switch locked is sustained by the sliding bolt and 20 the keeper lug.

A further advantage resulting from the present structure is that the switch can not be accidentally thrown open even if subjected to a severe shock due to a short 25 circuit.

I do not limit myself to the employment of my improved locking mechanism in connec-

tion with single throw switches, as the same may be applied to the type known as double throw switches.

Having now described my invention, I claim:

1. A device of the character described, having a pivoted switch blade, an extension projecting beyond the end of the blade in line therewith, a lever pivoted to said extension, a bolt in engagement with said lever and mounted to slide parallel with the edge of the blade, a switch jaw to cooperate with the blade, and a bolt keeper adjacent to the 40 base of said switch jaw.

2. An electric switch having a circuit-controlling blade pivoted at one end and having a housing provided with an eye beyond the other end of the blade in line therewith, 45 a bolt mounted to slide in a direction substantially parallel with and in the plane of one edge of the blade, a lever mounted in the housing and engaging the bolt and crossing the space within the eye of the housing, 50 and a fixed keeper for said bolt.

In testimony whereof I have affixed my signature.

RUDOLPH M. MARTENS.
